UNITED STATES PATENT OFFICE.

CLIFFORD G. KING, OF PROVIDENCE, RHODE ISLAND.

PIN.

Application filed November 10, 1925. Serial No. 68,139.

My invention relates to pins, brooches and the like and its principal object is to simplify the construction and reduce the cost of manufacture of the same.

5 Other objects of my invention are to provide a pin or brooch, or similar article in which the pin-tongue is attached directly to the front plate without a pintle or hinge connection whereby the construction is simplified and the cost of manufacture reduced, and specifically in which said pin-tongue is secured flexibly to said front plate whereby the life of the pin, brooch or other article is greatly increased, and the article in fact rendered practically indestructible.

10 Other objects of my invention are to provide such pin or like article in which the catch or pin-point-retaining means and the pin-tongue securing means are formed separately from the front plate and afterward inserted therein and secured thereto in any suitable manner.

15 With the foregoing and other objects in view, my invention comprises essentially a front plate and a pin-tongue of spring material bent upon itself and comprising an upper and a lower arm, together with means for flexibly securing the bent portion of the pin-tongue to the front plate at the end opposite the pin-point-retaining means, and means for flexibly securing the free end of the lower arm to the front plate.

20 While the means employed for flexibly securing the bent portion of the pin-tongue to the front plate may be formed separately from the latter, I prefer to use for this purpose oppositely-disposed ears integral with the front plate near the end thereof opposite the pin catch, the said ears extending 25 transversely over the lower arm of the pin-tongue forwardly of the bent portion thereof.

25 Illustrative embodiments of my invention are shown in the drawings which accompany and form a part of this specification, but it is to be understood that my invention may be embodied in numerous other forms and that said drawings are not to be considered as restrictive.

30 In the drawings—

Fig. 1 is a side elevation of a pin embodying my invention, said pin being shown many times its actual size for the purpose of clearly illustrating the details thereof,

and the several elements making up said pin 55 not being represented in exact proportion;

Fig. 2 is a plan view of said pin;

Fig. 3 is a transverse vertical section taken on the line 3—3 of Fig. 1;

Fig. 3^a is a transverse horizontal section 60 taken on the line 3^a—3^a of Fig. 1;

Fig. 4 is a side elevation of a modification;

Fig. 5 is a transverse vertical section taken on the line 5—5 of Fig. 4;

Fig. 6 is a central longitudinal vertical 65 section of a further modification;

Fig. 7 is a side elevation of the front plate of the pin shown in Fig. 6;

Fig. 8 is an end elevation of said front plate;

Fig. 9 is a side elevation of the pin-point-retaining catch of the pin shown in Fig. 6;

Fig. 10 is an end elevation of said catch;

Fig. 11 is a perspective view of the member 75 used in the pin shown in Fig. 6 for flexibly securing the bent portion of the pin-tongue to the front plate;

Figs. 12, 13 and 14 are sections taken on the lines 12—12, 13—13 and 14—14, respectively, of Fig. 6.

In the particular drawings selected for more fully disclosing my invention, 20 represents a front plate which may be ornamented or provided with an ornamental cover in the usual way and is provided with a catch or pin-point-retaining means 21 at one end, while the opposite end 22 is upturned for protecting and guiding the bent portion 23 of the pin-tongue which is of spring material and bent upon itself to form the upper arm 24 and the lower arm 25. The free end of the upper arm terminates in a point which is retained by the catch 21 while the free end of the lower arm terminates in an upstanding portion 26 located 90 within the vertical portion of said catch, as indicated in Fig. 2, the sides of said vertical portion being pressed inwardly, as shown at 27, to form a housing for the upstanding end 26 which is thus flexibly secured to the front plate in that it can move forwardly and backwardly within its housing and has a slight amount of side play.

95 Preferably the lower arm of the pin-tongue is flattened, but the upstanding end 26 is left round.

100 In order to flexibly secure the bent portion 23 of the pin-tongue to the front plate, I

provide the front plate, in the present instance, with a pair of oppositely-disposed ears 28, 28, the said ears preferably being integral with said front plate, and after the 5 pin-tongue has been inserted in position, the said ears are bent down so as to extend transversely over the lower arm of the pin-tongue forwardly of said bent portion.

It will be noted that the said ears 28, 28 10 do not press down tightly onto the lower arm of the pin-tongue, and that they therefore constitute a means, for flexibly securing the bent portion of the pin-tongue to the front plate. Preferably the outward end of 15 the said bent portion 23 does not touch the upturned end 22 of the front plate, as shown in Figs. 1 and 2, and the upstanding end 26 of the lower arm of the pin-tongue preferably is slightly spaced from the interior surface of the end wall of the catch 21, as indicated in Figs. 1, 2, and 3^a.

It will be obvious that the foregoing construction provides an exceedingly simple hingeless or pintleless pin, the part of which 25 may be economically assembled, and as no soldered joints are used, the pin members are not apt to become disengaged by even the hardest kind of usage, while the flexible connection of the pin-tongue to the front 30 plate greatly prolongs the life of the article, in fact rendering it practically indestructible.

In the modification shown in Fig. 4, the 35 free end 25' of the lower arm of the pin-tongue is flexibly secured to the front plate by means of a pair of ears 28, 28 formed on the trough-shaped member 29 (Fig. 11) which is set into the front plate near the catch 21 and secured thereto by rolling the 40 edges of said front plate over the edges 30, 30 of said member 29.

In the modification shown in Fig. 6 the 45 front plate 31 which is open-ended as shown in Fig. 8, is formed separately from the catch 32, and the latter is secured thereto by rolling the edges of said front plate over the edges 33 of the catch as indicated at 34, 34, Fig. 12, the base of said catch being 50 trough-shaped as indicated at 35, Fig. 10. Located within the front plate near the end 55 opposite the catch is a trough-shaped pin-retaining member 29, such as above described in connection with Figs. 4 and 11, and said member is secured to the front plate by rolling the edges of the latter over the edges 30 of said member as indicated at 36, 36, Fig. 14.

The upturned portion 26 of the free end 60 of the lower arm of the pin-tongue is retained in the vertical portion of the catch 21 in the manner above described in connection with Fig. 1 and the ears 28, 28 of the trough-shaped member 29 are bent over the lower arm 25 of the pin-tongue forwardly 65 of the bent portion 23 thereof, as above set

forth in connection with Fig. 1, so that in this instance also the bent portion of the pin-tongue is flexibly secured to the front plate at the end thereof opposite the pin-point-retaining means or catch, and the free end of the lower arm of the pin-tongue is flexibly secured to the catch which in turn is rigidly connected with the front plate.

This application is a continuation in part of my application Ser. No. 720,961, filed June 19, 1924.

Having thus described illustrative embodiments of my invention without however limiting the same thereto, what I claim and desire to secure by Letters Patent is:—

1. In a pin, a front plate having pin-point-retaining means at one end thereof, a pin-tongue of spring material bent upon itself and comprising an upper and a lower arm, and means for flexibly securing the bent 85 portion of said pin-tongue to said front plate at the end thereof opposite said pin-point-retaining means, the free end of said lower arm being flexibly secured to said front plate.

2. In a pin, a front plate having pin-point-retaining means at one end thereof, a pin-tongue of spring material bent upon itself and comprising an upper and a lower arm, means for flexibly securing the bent 95 portion of said pin-tongue to said front plate at the end thereof opposite said pin-point-retaining means, said means comprising oppositely-disposed ears extending transversely over the lower arm of said pin-tongue forwardly of said bent portion, and means for flexibly securing the free end of said lower arm to said front plate.

3. In a pin, a front plate having pin-point-retaining means at one end thereof, a pin-tongue of spring material bent upon itself and comprising an upper and lower arm, means integral with said front plate for flexibly securing said bent portion of said pin-tongue to said front plate at the end 105 thereof opposite said pin-point-retaining means, and means for flexibly securing the free end of said lower arm to said front plate.

4. In a pin, a front plate having pin-point-retaining means at one end thereof, a pin-tongue of spring material bent upon itself and comprising an upper and a lower arm, and means for flexibly securing the bent portion of said pin-tongue to said front plate 115 at the end thereof opposite said pin-point-retaining means, the end of said lower arm being flexibly secured to said front plate.

5. In a pin, a front-plate having pin-point-retaining means at one end thereof, a pin-tongue of spring material bent upon itself and comprising an upper and a lower arm, means for securing the bent portion of said pin-tongue to said front plate at the end thereof opposite said pin-point-retain- 125 130

ing means, and means for securing said lower arm to said front plate, the last mentioned means consisting of a trough-shaped member inserted in and secured to said front plate and provided with ears extending transversely over said lower arm.

6. In a pin, a front plate having pin-point-retaining means at one end thereof, a pin-tongue of spring material bent upon itself and comprising an upper and a lower arm,

means for flexibly securing the bent portion of said pin-tongue to said front plate at the end thereof opposite said pin-point-retaining means, and means for flexibly securing the free end of said lower arm to said front plate.

In testimony whereof, I have hereunto subscribed my name this 30th day of October, 1925.

CLIFFORD G. KING.
